UNITED STATES PATENT OFFICE.

SAMUEL STENGER AND JOHN CALVIN MALLORY, OF ALTOONA,
PENNSYLVANIA.

GOODS-EXHIBITOR.

SPECIFICATION forming part of Letters Patent No. 734,444, dated July 21, 1903.

Application filed March 19, 1903. Serial No. 148,558. (No model.)

To all whom it may concern:

Be it known that we, SAMUEL STENGER and JOHN CALVIN MALLORY, citizens of the United States, and residents of Altoona, in the county of Blair and State of Pennsylvania, have invented a new and Improved Goods-Exhibitor, of which the following is a specification.

Our invention relates to goods-exhibitors for displaying merchandise—such as oil-cloth, linoleum, matting, carpets, and the like—in rolls or bolts.

The invention consists of the novel features, details of construction, and combination of the parts which hereinafter will be fully disclosed and finally claimed.

While the essential and characteristic features of the invention are necessarily susceptible of modification, still the preferred embodiment thereof is illustrated in the accompanying drawings, forming a part of this specification.

In the drawings, Figure 1 is a view showing our invention in side elevation. Fig. 2 is a similar view, part in section. Fig. 3 is a top plan view, and Fig. 4 is a horizontal section through the standard and hinged arms looking down.

In carrying out our invention we employ a platform A, supported by rollers A' of any approved type.

C denotes a suitable standard projecting up from the platform A and having suitable braced support thereon. At the upper end of this standard we provide a series of perforations C', a projecting pin C², and a washer C³, which latter is supported by the pin C², as shown.

The features above described constitute the supporting means for our improved rotatable goods-holder, which we will describe as follows:

In constructing our goods-holder we employ a base D, having concentrically located therethrough a vertical perforation D', adapted to receive the standard C. On the under side of the base D a series of rollers D² are arranged, which travel upon a circular track D³ on the platform A. In connection with the base D we employ an upper circular or other shaped head E, which is fixed on a tube

E' at the upper end thereof. The tube E' is made depending, as shown, and adapted to receive the standard C. The lower end of the tube E' rests upon the washer C³, and thereby providing support for the head E. The perforations C' in the standard C afford adjustment of the head E, which is effected by changing the pin C² from one to another of said perforations C', as will be understood.

With our invention we employ a series of arms F, having hinged connection F' at their lower ends with the base D. The arms F are located in circular arrangement, as shown, and with their upper ends adapted to engage with perforations F² of projecting spring-catches F³, fixed to the upper side of the head member E. It will be noticed that the outer edge of the head E is provided with recesses F⁴, adapted to receive and support the upper ends of the arms F when they are in engagement with the catches F³. At the lower end of the arms F we provide a rotatable support G, whereby the lower edge of the roll of goods on the arms is protected in unwinding or winding action thereof, as will be understood.

H indicates a suitable knife having sliding support on a rod H'. This rod is held in vertical position by having its lower end stepped into a suitable socket I on the base D and with its upper end extended through a suitable keeper J, fixed to the head E, as shown. It will be noticed that a socket I and keeper J are located about half-way between each two arms F of the series. According to our invention one knife will serve for cutting the goods of either roll thereof on the exhibitor, and it may be changed from roll to roll by lifting and withdrawing its supporting rod H' from the socket I and keeper J and rearranging it in the desired holders I J, which are provided therefor between each hinged arm F on the exhibitor.

Our improved knife-support has advantage not only in its adjustability, but also of the fact that it provides means whereby cutting of the goods with squared ends is facilitated.

Having thus described our invention, what we claim as new, and desire to secure by Letters Patent, is—

1. The combination with a goods-exhibitor

of the character described, vertically-supported arms having hinged connection at one end with a suitable base, a head member having catch devices thereon adapted for engagement with the upper ends of the said arms, and a sliding guided knife, adapted for cutting goods on the said arms substantially as described.

2. The combination in an exhibitor of the character described employing a platform and a standard as specified, goods-supporting means consisting of a base with rollers on its under side, a head member having adjustable support on the said standard, a series of arms having hinged connection at their lower ends with the said base, catches on the said head member adapted for locking engagement with the upper ends of the said hinged arms, a rotatable support at the lower end of each hinged arm, recesses in the outer edge of the said head adapted to receive the upper ends of the said hinged arms, a knife

having guided support on a suitable rod, sockets on the said base and keepers on the said head located and adapted for supporting the said knife-guiding rod, substantially as described.

3. In combination with a rotatable exhibitor of the character described having a series of roll-holding arms as specified, the said arms having hinged connection with a suitable base, means adapted for securing the free ends of the said arms, goods-cutting means, consisting of a knife having sliding movement on a guiding-rod, and means between each two roll-holding arms of the series, adapted for supporting the said knife-guiding rod, substantially as described.

SAMUEL STENGER.
JOHN CALVIN MALLORY.
